FRED MARTIN WHITMAN, OF TUCSON, ARIZONA TERRITORY.

ROTARY ENGINE.

No. 909,493.

Specification of Letters Patent.

Patented Jan. 12, 1909.

Application filed January 28, 1908. Serial No. 413,018.

To all whom it may concern:

Be it known that I, FRED MARTIN WHITMAN, a citizen of the United States, and a resident of Tucson, in the county of Pima and Territory of Arizona, have invented a new and Improved Rotary Engine, of which the following is a full, clear, and exact description.

The object of the invention is to provide a new and improved rotary engine, arranged to permit convenient reversing and to utilize the motive agent to the fullest advantage.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a cross section of the improvement, on the line 1—1 of Fig. 2; Fig. 2 is a sectional plan view of the same on the line 2—2 of Fig. 1; Fig. 3 is a transverse section of the same on the line 3—3 of Fig. 1; Fig. 4 is an enlarged plan view of the automatic abutment; Fig. 5 is an end view of the same; Fig. 6 is an enlarged sectional side elevation of the improvement; Fig. 7 is a side elevation of the rotor; Fig. 8 is an end view of the same; Fig. 9 is an enlarged sectional side elevation of the packing for the rotor in the cylinder, and Fig. 10 is a cross section of the improvement showing the rotor and the automatic abutment in a different position from the one shown in Figs. 1 and 6.

In the cylinder A of a rotary engine is mounted to turn the rotor B, secured on the shaft C, journaled in suitable bearings D, carried by spiders E attached to the cylinder A at the open ends thereof. The rotor B is provided on its peripheral face with a head B' in frictional contact with the inner surface of the cylinder A. The cylinder A is intersected at the top by the abutment seat F, containing an automatic oscillating rotor abutment G in frictional contact with the peripheral surface of the rotor B, to form with the latter a working chamber in the cylinder A, with a view to turn the rotor B in either a forward direction, as indicated by the arrow a', or in the inverse direction thereof, as hereinafter more fully explained. The rotor abutment G is made hollow and consists es-

sentially of trunnions G', journaled in the ends of the rotor seat F, and the trunnions G' are connected with each other by a cross piece G², having its ends connected with each other by a rim G³, fitting the peripheral face of the seat F. The rim G³ of the hollow abutment G is provided with sets of ports a, b and c, d, adapted to register with ports e, f, formed on top of the seat F, and controlled by a reversing slide valve H, arranged in a steam chest I, connected by a pipe J with a boiler or other suitable motive agent supply, the said pipe J being provided with a valve J' and a by-pass J'', as indicated in Fig. 1.

The slide valve H is provided with a valve stem H', connected at its outer end by a link H² with a hand lever H³, under the control of the operator, to permit the latter to shift the slide valve H from the position shown in Figs. 1 and 6 to that illustrated in dotted lines in Fig. 6. The slide valve H is provided with the ports g and h, of which the port g is adapted to register with the port f, as shown in Figs. 1 and 6, while the port h is adapted to register with the port e whenever the valve H is shifted into the reversing position indicated in dotted lines in Fig. 6. Into the valve seat F open the exhaust ports i and j, opened or closed by the slide valve H, and connected with the exhaust pipes K and K', for carrying the exhaust motive agent to a suitable place of discharge. When the slide valve H is in the position shown in Figs. 1 and 6, the exhaust port i is closed while the exhaust port j is open, and when the valve H is reversed then the port i is opened and the port j is closed.

Transversely through the hollow abutment valve G extends a fixed abutment F', forming part of the abutment seat F, to direct the steam or other motive agent into either side of the abutment G, to hold the latter in a forward or reverse position, as indicated in full and dotted lines in Fig. 6. When the several parts are in the position shown in Figs. 1 and 6, the ports e, h, c and i are closed, while the ports b, g, d and j are open, so that the motive agent in the steam chest I can pass by way of the registering ports g, f and b into the hollow abutment G and through the same and by way of the port d into the working chamber of the cylinder A, to press against the head B' of the rotor B, to rotate the latter in the direction of the

arrow a' . The exhaust motive agent in front of the head b' passes through the exhaust port j and pipe K' to a suitable place of discharge. Now it will be noticed that by having the fixed abutment F' extending through the rotor abutment G , the motive agent holds the rotor abutment G in the position indicated in Figs. 1 and 6, and allows the said rotor abutment to yield and oscillate in the direction of the arrow b' whenever the head B' comes around. During this movement of the abutment G the port b is cut off from the port f for the time being, and in order to prevent the abutment G from turning over into a reversing position, a small port k is provided in the rim G^3 , to move in register with the port f during the time the abutment G is turned by the head B' of the rotor B to permit steam to pass into the rotor abutment and to counter-balance the same. When the operator desires to reverse the engine, he moves the hand lever H^2 into the position shown in dotted lines in Fig. 1, so that the port g is moved out of register with the port f , while the port h moves in register with the port e . At the same time the valve H opens the exhaust port i and closes the exhaust port j . The motive agent in the steam chest I now passes by way of the registering ports h , e , a into the interior of the rotor abutment G , at the right hand side of the fixed abutment F' , so that the abutment G by the pressure of the steam is caused to turn into the position shown in dotted lines in Fig. 6. When this takes place the port e moves into register with the port a while the port a opens into the cylinder A at the right hand side of the rotor abutment G , and consequently the rotor B is now caused to rotate in the reverse direction of the arrow a' . When the rotor abutment G turns into the reverse position shown in dotted lines in Fig. 6, then the port i is opened to permit the exhaust motive agent in front of the head B' to pass by way of the port i and the pipe K to a place of discharge.

In order to hold the abutment G in the reverse position and during the time the abutment G is caused to slightly oscillate at the time the head B' passes the abutment, steam is passed into the abutment by way of a small port k' formed in the rim G^3 of the abutment, and adapted to register with the port e when the port e is cut off during the oscillation of the abutment G by the passage at the head B' and a small port l is arranged between the ports k , k' in the rim G^3 of the abutment G to admit a small amount of motive agent into the abutment G to act in the same manner when the rotor is in the reverse motion.

In order to render the rotor B as steam-tight as possible in the cylinder A , the peripheral face of the rotor is provided with angular packing-rings L , made of steel or other suitable material, and having outwardly-

extending members L' (see Fig. 9), sufficiently thin to be pressed outward by the motive agent and in contact with the wall of the recess A' formed in the cylinder, and in which fit the flexible members of the packings L .

The by-pass J^2 is used to admit at all times live motive agent to the steam chest I , to prevent shifting of the abutment G accidentally, after the motive agent is cut off by the valve J' and the rotor B is still rotating by its own momentum.

The rotary engine shown and described is simple and durable in construction, composed of comparatively few parts not liable so easily to get out of order, and the engine can be readily reversed at any time by the operator simply manipulating the hand-lever H^2 , as above described.

Having thus described my invention, I claim as new and desire to secure by Letters Patent:

1. A rotary engine comprising a cylinder, a rotor therein, a hollow oscillating rotor abutment for engagement with the peripheral face of the said rotor, the said rotor abutment having ports for connection with a motive agent supply and with the said cylinder, and a fixed abutment extending through the said rotor abutment.

2. A rotary engine comprising a cylinder, a rotor therein, a hollow oscillating rotor abutment for engagement with the peripheral face of the said rotor, the said rotor abutment having ports for connection with a motive agent supply and with the said cylinder, a fixed abutment extending through the said rotor abutment, and a reversing valve controlling the admission of the motive agent to the said oscillating rotor abutment.

3. A rotary engine comprising a cylinder, a rotor therein, a hollow oscillating rotor abutment for engagement with the peripheral face of the said rotor, the said rotor abutment having ports for connection with a motive agent supply and with the said cylinder, a fixed abutment extending through the said rotor abutment, and a manually-controlled reversing slide valve for controlling the admission of the motive agent to the said oscillating rotor abutment.

4. A rotary engine comprising a cylinder, a rotor therein, an oscillating rotor abutment made hollow and having sets of ports in its peripheral face, a fixed abutment extending transversely through the said hollow rotor abutment, a steam chest connected with a steam supply, and a manually-controlled reversing valve in the said steam chest for controlling the admission of steam into the said hollow rotor abutment at either side of its fixed abutment.

5. A rotary engine comprising a cylinder, a rotor therein, an oscillating rotor abutment made hollow and having sets of ports in its

- peripheral face, a fixed abutment extending transversely through the said hollow rotor abutment, a steam chest connected with a steam supply, a manually-controlled reversing valve in the said steam chest for controlling the admission of steam into the said hollow rotor abutment at either side of its fixed abutment, and a by-pass for continuously conducting steam to the said steam chest.
10. 6. A rotary engine provided with a cylinder, a rotor therein, and packing rings on the peripheral face of the said rotor and having flexible members fitting into annular recesses in the cylinder and pressed against the walls

of the recesses by the pressure of the motive agent.

7. A rotary engine comprising a cylinder, a rotor therein, and flexible annular members on the peripheral face of the rotor, adapted to be pressed against the wall of the cylinder by the motive agent for the purpose set forth.

In testimony whereof I have signed my name to this specification in the presence of two subscribing witnesses.
